UNIT VENTILATOR CONTROL SYSTEM

Wayland R. Miller, Chicago, Ill., assignor to
Minneapolis-Honeywell Regulator Company,
Minneapolis, Minn., a corporation of Delaware

Application April 3, 1936, Serial No. 72,521

2 Claims. (Cl. 98—1)

This invention relates to control systems for unit ventilators.

It is an object of this invention to provide a control system for unit ventilators wherein a plurality of unit ventilators may be rendered operative or inoperative from a remote point and wherein each unit ventilator may be rendered operative or inoperative independently as desired.

The specific manner in which this mode of operation is accomplished and the structure utilized in accomplishing this mode of operation also form objects of this invention.

Other objects and advantages will become apparent to those skilled in the art upon references to the accompanying specification, claims and drawing.

For a more thorough understanding of my invention, reference is made to the accompanying single sheet of drawings in which is diagrammatically illustrated the preferred form of my invention.

A plurality of spaces to be conditioned and ventilated are designated at 10 and in each of the spaces are located unit ventilators 11 which may be of the type shown and described in application Serial No. 44,899 filed by John T. Midyette, Jr., on October 14, 1935. One of the unit ventilators 11 is shown in section for purposes of illustration. The unit ventilators 11 may contain heat exchangers 12 which may be supplied with conditioning fluid under the control of valves 13. The damper 14 regulates the amount of recirculated or return air and the amount of outdoor air supplied by the fans 15 to the heat exchangers 12. The fans 15 are operated by a motor 16. The valves 13 and the mixing damper 14 may be controlled by a proportioning motor 18 in the manner described in the above referred to Midyette application. Power is supplied to the proportioning motor by a transformer 19, the secondary of which is connected thereto by means of wires 20. Each ventilator is provided with terminals 44 and 45. One terminal each of the transformer 19 and the fan 16 is connected to terminal 44 through wires 35, 36 and 37. The other terminals of the transformer and fan are connected through wires 38, 39 and 40 to terminal 45.

Each unit ventilator 11 is provided with a single pole double throw snap switch generally designated at 21 for placing the ventilators in or out of operation. Located in some convenient point, as in the basement, is a single pole double throw master snap switch generally designated at 22. The snap switch 22 may comprise a switch arm

23 adapted to engage spaced contacts 24 and 25. Likewise, the snap switches 21 may comprise switch arms 26 adapted to engage spaced contacts 27 and 28.

A hot line 30 leading from a source of power, not shown, is connected to the switch arm 23 of the master snap switch 22. The contact 24 thereof is connected by wires 31 and 32 to the contacts 28 of the snap switches 21 associated with the unit ventilators 11. Likewise, the contact 25 of the master snap switch 22 is connected by wires 33 and 34 to the contacts 27 of the snap switches 21 of the unit ventilators 11. The switch arms 26 of the snap switches 21 are connected to the terminals 44. The other terminals 45 are in turn connected through wires 46 and 41 to the ground line wire 42.

By reason of the above wiring connections when the switches 21 and 22 are in the "day" positions shown, the fan motors 16 and the transformers 19 are energized whereby the various unit ventilators 11 are controlled in the manner disclosed in the above referred to Midyette application. At night the attendant in charge of the particular building moves the switch arm 23 from engagement with the "day" contact 24 into engagement with the "night" contact 25. This breaks the power circuits to the various unit ventilators 11 and the unit ventilators 11 are then rendered inoperative for the night.

If an occupant of any space or room wishes to have the unit ventilator 11 of that room in operation during the night, he moves the switch arm 26 from the "day" contact 28 into engagement with the "night" contact 27 whereby the power circuit to the unit ventilator 11 of that space is completed to cause operation of that unit ventilator. When the occupant of the room no longer wants the unit ventilator in operation during the night time, he moves the switch arm 26 out of engagement with the "night" contact 27 and into engagement with the "day" contact 28 to stop operation of that unit ventilator and to condition that unit ventilator for operation in the morning when the switch arm 23 of the master snap switch 22 is moved from engagement with the "night" contact 25 into engagement with the "day" contact 24.

If an occupant of a space desires to shut down the unit ventilator of that space during the day time, he moves the switch arm 26 of the snap switch 21 out of engagement with the "day" contact 28 and into engagement with the "night" contact 27 whereby the power circuit to that unit ventilator is broken. When the occupant of

that room again desires to have the unit ventilator 11 of that room placed in operation, he moves the switch arm 26 out of engagement with the "night" contact 27 and into engagement with the "day" contact 28 whereupon the unit ventilator 11 is again rendered operative.

From the above it is seen that I have provided a control system for unit ventilators wherein all of the unit ventilators may be controlled from 10 a remote point and wherein each unit ventilator may be controlled independently as desired.

Although I have shown one form of my invention for purposes of illustration, other forms thereof may become obvious to those skilled in 15 the art and consequently this invention is to be limited only by the scope of the appended claims and prior art.

I claim as my invention:

1. In a system of the class described, a plurality of unit ventilators for a plurality of spaces, each of said unit ventilators including conditioning, ventilating and control means, a single pole double throw switch associated with each unit ventilator, a master single pole double throw 25 switch, a pair of line wires for supplying electrical energy to said unit ventilators, a first of said line wires being connected to the switch arm of the master switch and the second of said wires

being connected to the ventilating and control means of each unit ventilator, connections between the contacts of the master switch and the contacts of each switch associated with said unit ventilators, and connections between the ventilating and control means and the switch arm of the switch associated with that unit ventilator whereby the unit ventilators may be controlled by the master switch and by the switches associated therewith. 5

2. In a system of the class described, a plurality of unit ventilators, a single pole double throw switch associated with each unit ventilator, a master single pole double throw switch, a pair of line wires for supplying electrical energy 15 to said unit ventilators, one of said line wires being connected to the switch arm of the master switch and the other of said line wires being connected to the unit ventilators, connections between the contacts of the master switch and the 20 contacts of each switch associated with said unit ventilators, and connections between each unit ventilator and the switch arm of the switch associated therewith whereby the unit ventilators may be controlled by the master switch and by 25 the switches associated therewith.

WAYLAND R. MILLER.
